COMBINATION ELECTRICAL OUTLET
AND CORD COVER

Tony Gonzalez, 510 E. 86th St.,
New York, N.Y. 10028

Filed Dec. 22, 1966, Ser. No. 5,155

Term of patent 14 years

(Cl. D26—13)

FIG. 1 is a perspective view of the combination electrical outlet and cord cover showing my new design;

FIG. 2 is a front elevational view of the cover;

FIG. 3 is a side view of the cover;

FIG. 4 is a bottom plan view of the cover; and

FIG. 5 is a rear elevational view of the cover on reduced scale.

I claim:

The ornamental design for a combination electrical outlet and cord cover, as shown.
